(57) **CLAIM**

The ornamental design for a display panel with icon, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display panel with icon showing our new design; and,

FIG. 2 is a front view of the display panel with icon showing the icon enlarged and separate for clarity.

The equal length broken lines in FIG. 1 show the display panel and form no part of the claimed design. The dash-dot broken lines in FIGS. 1 and 2 define the bounds of the claimed design and form no part thereof.
